ABSTRACT

A tool for rotating nuts remotely located in a confined space and comprising a wrench head for engaging the nut, a handle bar, and a pair of connecting arms disposed parallel to each other with one end of one arm pivotally connected to the handle and the other end pivotally connected to one side of the wrench head, and with one end of the other arm pivotally connected to the handle and the other end pivotally connected to the opposite side of the wrench head.

3 Claims, 2 Drawing Figures

TOOL FOR REMOVING AND INSTALLING WATER METERS

BACKGROUND OF THE INVENTION

1. Field of the Invention

The present invention relates generally to wrenches and more particularly, to a special purpose wrench having particular utility relative to the installation and maintenance of water meters.

2. Description of the Prior Art

Water meters are normally installed within a relatively small housing which, because of the proximity of the side walls, severely restricts the use of ordinary wrenches to tighten or loosen nuts connecting water pipes to the meter. One prior art attempt to provide a special purpose tool for use in this environment is disclosed in the U.S. Pat. to Harris, No. 3,691,877. However, the Harris patent suffers from the disadvantage that its operation is complex in terms of manipulative steps.

OBJECTS OF THE PRESENT INVENTION

It is therefore a principal objective of the present invention to provide an improved water meter nut turning tool which is simple in structure and easy to use.

Briefly, the preferred embodiment of the present invention is comprised of a wrench head for engaging a nut located in a confined space, a handle bar, and a pair of connecting arms disposed parallel to each other with one end of one arm pivotally connected to the handle and the other end pivotally connected to one side of the wrench head, and with one end of the other arm pivotally connected to the handle and the other end pivotally connected to the opposite side of the wrench head.

Among the advantages of the present invention is that the particular configuration of handle, wrench head and connecting arms permits the head to rapidly engage and disengage a nut while also enabling substantial turning leverage to be applied thereto.

Other objects and advantages of the present invention will become apparent to those skilled in the art after having read the following detailed disclosure of the preferred embodiment illustrated in the several figures of the drawing.

IN THE DRAWING

FIG. 1 is a front view illustrating a wrench in accordance with the present invention.

FIG. 2 is a side view of the wrench illustrated in FIG. 1.

DETAILED DESCRIPTION OF THE PREFERRED EMBODIMENT

Referring now to the drawing, a preferred embodiment of the invention is disclosed which includes a wrench head 10, a pair of connecting arms 12 and 14, and a handle bar 16.

Head 10 is comprised of a generally octagonally-shaped plate made of heavy gauge, high strength metal and having nut engaging notches 18, 20, 22 and 24 cut in four of its eight sides. As illustrated, the notches are five-sided for engaging octagonal nuts, but may alternatively be of any other configuration suited for engaging other types of nuts. Head 10 is also provided with three pairs of round apertures 26, 28 and 30 which are positioned relative to the several notches as illustrated.

Connecting arms 12 and 14 are of identical structure and each includes an elongated shaft portion of any suitable length which terminates in a bifurcated lower end portion 32 for receiving head 10 and a bifurcated upper end portion 34 for receiving handle bar 16. The branch members 36 and 38 forming end portion 32 are thickened slightly at 40 and 42 respectively, to provide bearing surfaces for engaging the sides of head 10, and are bored as indicated to receive the pivot pins 44. Pivot pins 44 are locked in place by suitable locking means such as the cotter keys 46.

The upper end portions of arms 12 and 14 are pivotally attached to handle bar 16 by suitable rivets, bolts or the like as illustrated at 48. The two connections are made at points equidistant from the respective ends of the handle. The length of bar 16 is selected suitable to allow sufficient differential leverage to be applied to head 10 to break loose even the tightest threaded nuts. As indicated previously, the arms 12 and 14 must at all times be parallel, therefore the respective spacings between the handle pivot points and head pivot points must be equal.

In operation, the pins 44 are removed and the head is rotated until the notch corresponding to the particular nut to be loosened (or tightened) is located in the position shown occupied by notch 18. The pins are then replaced to attach the arms to the pair of apertures nearest the selected notch, and the wrench is applied to the nut while holding one end of handle 16 in each hand. One handle end is then pushed and the other pulled depending upon the desired direction of turn, and the resulting torque forces are transmitted through arms 12 and 14 to head 10 to turn the nut. It is important to note that it is necessary to rotate the arms 12 and 14 (about the nut axis) as was required with prior art devices in order to apply large torque forces to the nut. Quite to the contrary, in using the present invention the turning torque is applied to the nut with no revolution whatsoever of the connecting arms. Thus, the device can be used in any case where the access passageway is large enough to admit the wrench head.

Although it is contemplated that after having read the preceding disclosure certain alterations and modifications of the present invention will no doubt become apparent to those skilled in the art, it is intended that the following claims be interpreted to cover all such alterations and modifications as fall within the true spirit and scope of the invention.

What is claimed is:

1. A wrench device comprising:

a wrench head having at least one notch configured to mate with an object to be rotated;
an elongated handle bar; and
a pair of elongated connecting arms disposed in parallel with each other, said arms respectively having one end pivotally connected to different ones of a pair of separated points along the mid-portion of said handle bar and an opposite end pivotally connected to said head at one of a pair of points which are respectively equidistant from opposite sides of said notch.

2. A wrench device as recited in claim 1 wherein said wrench head includes a plurality of notches of different sizes.

3. A wrench device as recited in claim 1 wherein each said end of each of said connecting arms is bifurcated to respectively receive said handle bar and said wrench head and wherein said pivotal connections are made by pins which respectively pass through said one end and said handle, and through said opposite ends and said wrench head.
